(57) **CLAIM**

The ornamental design for a counter, as shown and described.

DESCRIPTION

FIG. 1 is a front view of one embodiment of a counter embodying my new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a front view of another embodiment of a counter embodying my new design;

FIG. 8 is a rear view thereof;

FIG. 9 is a right side view thereof;

FIG. 10 is a left side view thereof;

FIG. 11 is a top view thereof; and,

FIG. 12 is a bottom view thereof.

The broken lines of the handles are for the purpose of illustrating environment only and form no part of the claimed design.
